TOP STOP FOR SLIDE FASTENER TAPES

Max Kiessling, Waterbury, Conn.

Application December 19, 1938, Serial No. 246,602

1 Claim. (Cl. 24—205

This invention relates to slide fasteners, and more particularly to an improved form of top stop for the slider member to be attached to a pair of cooperating element-holding tapes.

5 When slide fastener tapes are applied to the opposite sides of the opening in a bag, or the like, it has been found that if an attempt is made to close the edges of the opening together at the top of the tapes, the slider member and 10 elements are likely to become jammed. By means of the present invention, the above and other disadvantages have been overcome.

One object of this invention is to provide an 15 improved top stop for the slider member which will maintain the beaded edges of the tapes at the upper end of the opening at each side of the stop spaced apart both above and below the top stop an amount substantially equal to the 20 distance between the diverging outlets at the top of the slider member.

Another object is to provide a top stop device 25 of the above nature which will have at its bottom an arcuate recess shaped to substantially fit the top bridge, or neck of the slider member.

Still another object is to provide a stop device 30 of the above nature having means to securely grip the opposing beaded edges of the tapes for holding said edges spaced apart the same distances above and below said stop device.

A further object of this invention is to provide 35 an improved top stop for slide fastener tapes of the above nature which will be relatively inexpensive to manufacture, simple in construction, compact, ornamental in appearance, and very efficient and durable in use.

With these and other objects in view, which will appear as the description proceeds, there has been illustrated on the accompanying drawing, one form in which the invention may be conveniently embodied in practice.

In the drawing:

Fig. 1 is a front plan view of a stop device for the slider member of a pair of slide fastener tapes as it appears when in its uppermost position with the opening closed.

Fig. 2 is a view similar to Fig. 1 showing the slider member as it appears in partially open position.

Fig. 3 is an enlarged bottom view of the stop device,—the beaded edges of the tapes being shown in section, looking upwardly in the direction of the arrows 3—3 of Fig. 2.

Fig. 4 is a sectional view of the stop device taken on the line 4—4 Fig. 3.

Fig. 5 is a development view of the stop device

in flat condition before bending it into U-form for attachment to the beads of a pair of slide fastener tapes.

Referring now to the drawing, wherein like reference characters designate like parts 5 throughout the several views, the numerals 10 and 11 indicate a pair of adjacent element-holding tapes of a slide fastener having opposing beaded edges 12 and 13 respectively, along which two spaced rows of fastening elements 14 10 and 15 of the usual form are securely clamped.

The fastening elements 14 and 15 are adapted to be interlocked and unlocked by means of a slider member 16 of the usual form which may be readily slid along between the beaded edges 15 12 and 13 by means of a hinged pull tab 17.

In order to limit the upward movement of the slider member 16, provision is made of a top stop 18 which is adapted to be disposed at the upper end 19 of the opening 20 between the 20 beaded edges 12 and 13 of the tapes 10 and 11, and is adapted to hold said beaded edges permanently spaced apart at said upper end a predetermined amount which is preferably equal to the distance between the outlets at the top of 25 the flared end 21 of the slider member 16. By means of this construction it will be seen that the top portion of the tapes will lie flat and parallel to each other when the fastening members 14 and 15 are in unlocked position (see Fig. 30 2). The top stop 18 is also adapted to hold the beaded edges 12 and 13 spaced apart above the upper side of the stop device 18 an amount equal to the distance they are spaced apart below it.

The top stop 18 is preferably made by stamping 35 a blank 22 (see Fig. 5) from sheet metal and then forming four inclined grooves 23, 24, 25 and 26 upon the inclined wing portions 27, 28, 29 and 30 thereof. The wing portions 27 and 29 are connected together by a side plate 31 which is 40 cut away at its outer edge to form an arcuate recess 32. The wing portions 28 and 30 are similarly connected together by a side plate 33 which is cut away at its outer edge to form an arcuate 45 recess 34. The wing-connecting side plates 31 and 33 are joined together by a center neck portion 35. The spacing between the grooves 23, 24 and 25, 26 is equal to the distance it is desired to hold the beaded edges 12 and 13 apart 50 at the upper part of the tapes. The depth of the recesses 32 and 34 is substantially equal to the width of the protruding neck 36 of the flared portion 21 of the slide member 16, so that the opening 19 between the tapes at this point will 55

be substantially filled when the slide member 16 abuts the stop device 18, as shown in Fig. 1.

The inclined grooves 23, 24, 25 and 26 have sharp edges which "bite" into the surfaces of the beads 12 and 13 to strengthen the grip of the top slider stop thereon and effectively prevent said beads from sliding or twisting with respect to said stop without injury to said beads.

Assembly

- 10 The top stop device 18 is adapted to be assembled to the tapes 10 and 11 by first disposing the blank 22 in such a position that the inclined wings 28 and 30 will lie underneath the tapes 15 10 and 11, and with the beaded edges 12 and 13 resting across the inclined grooves 24 and 26. The wings 27 and 29 will then be bent down upon the beaded edges 12 and 13,—the neck portion 35 being arcuately bent as shown in Fig. 4. 20 It will thus be seen that the beaded edges 12 and 13 will be tightly clamped between the wings 27, 29 and 28, 30, respectively, so that the top stop 18 will be securely attached to the tapes 10 and 11.
- 25 When the top stop 18 is in assembled position, the recesses 32 and 34 will be parallel and will form a seat for the protruding neck 36 of the slide member 16.
- One advantage of the present invention is that 30 in use no binding will occur between the slider member 16 and the fastening elements 14 and 15,

nor with the stop device 18. Furthermore, the beaded edges 12 and 13 both above and below the stop device 18 will be maintained in alignment and spaced apart an amount equal to the spacing of the outlets of the flared portion 21 5 of the slider member 16.

While there has been disclosed in this specification one form in which the invention may be conveniently embodied, it is to be understood that this form is shown for the purpose of illustration only, and that the invention is not to be limited to the specific disclosure, but may be modified and embodied in various other forms without departing from its spirit. In short, the invention includes all of the modifications and 15 embodiments coming within the scope of the following claim.

Having thus fully described the invention, what is claimed as new and for which it is desired to 20 secure Letters Patent, is:

A top stop device for a slide fastener wherein a pair of tapes having opposing beaded edges are provided, said device including a pair of opposing flat side plates a U-shaped portion connecting said side plates, each side plate having 25 a pair of wing portions, said wing portions being provided with converging opposed grooves to engage the beaded edges of said tapes to hold them in spaced apart relation.

MAX KIESSLING. 30
